(57) **CLAIM**

The ornamental design for a watch, as shown and described.

DESCRIPTION

FIG. 1 is a perspective view of a watch of the present invention showing our new design;

FIG. 2 is a top plan view of the watch of FIG. 1;

FIG. 3 is a front elevational view of the watch of FIG. 1, the rear elevational view being a mirror image thereof; and, FIG. 4 is a right end elevational view of the watch of FIG. 1, the left end elevational view being a mirror image thereof. Broken lines shown in the drawings are used to indicate the environment in which the design is used, but form no part of the claimed design. The bottom plan view is unornamental and forms no part of the claimed design.
